UNITED STATES PATENT OFFICE

155,753

DESIGN FOR A FOOD SERVER

Ruth S. Warner, Chicago, Ill.

Application September 10, 1947, Serial No. 141,291

Term of patent 3½ years

(Cl. D44—10)

To all whom it may concern:

Be it known that I, Ruth S. Warner, a citizen of the United States, residing at Chicago, in the county of Cook and State of Illinois, have invented a new, original, and ornamental Design for Food Server, of which the following is a specification, reference being had to the accompanying drawing, forming a part thereof.

Fig. 1 is a plan view of a food server, embodying my new design; and

Fig. 2 is a side elevational view of the same.

I claim:

The ornamental design for a food server, substantially as shown.

RUTH S. WARNER.
